G. J. SEISS.

INSULATED KNOB FOR RADIO INSTRUMENTS.

FILED JUNE 9, 1922.

INVENTOR
George J. Seiss
Owen Owen & Grampston

UNITED STATES PATENT OFFICE.

GEORGE J. SEISS, OF TOLEDO, OHIO.

INSULATED KNOB FOR RADIO INSTRUMENTS.

Application filed June 9, 1923. Serial No. 566,944.

To all whom it may concern:

Be it known that I, GEORGE J. SEISS, a citizen of the United States, and a resident of Toledo, in the county of Lucas and State 5 of Ohio, have made an invention appertaining to an Insulated Knob for Radio Instruments; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 My invention has for its object to provide a simple and yet efficient insulating knob for radio instruments. It is used particularly for adjustably locating movable parts of radio instruments and positioning such 20 parts to obtain the best results in the manner well known in the art.

The invention may be used in connection with insulated knobs of different forms. To 25 illustrate a practical application of the invention I have selected a knob embodying the invention and shall describe it herein-after. The knob selected is illustrated in the accompanying drawings.

Figure 1 of the drawings is a front 30 view of the knob. Fig. 2 is a sectional view taken on the line 2—2. Fig. 3 illustrates a side view of a means for connecting the shank or rod to the knob.

The knob 1 comprises a shell 2 that may 35 be formed of sheet material, such as sheet metal, that may be readily stamped and manipulated in the manner well known in the arts of sheet metal stamping, spinning and drawing. Thus the knob may be very 40 easily made by the ordinary die press and spinning devices or machines. The peripheral portion 3 is raised to form a ridge of considerable width and a cross section in the form of an arc having a radius of relatively considerably length. Thus a gripping 45 portion is formed that is of such a character that the knob may be conveniently operated and delicate adjustments may be obtained.

50 The central portion 4 is lens-shaped, the other side being convex and forming with the peripheral portion of the knob an annular recess 5 in the outer surface of the knob and a distinct ridge 6 on the inside, and within 55 the area defined by the ridge 3. A disc 7, which is formed of sheet insulating material

such as fibre board, that may be readily formed by a die press, is located within the edge portion of the sheet material forming the shell 2. The disc 7 substantially fits 60 within the edge portion of the shell and is placed against the ridge 6 which is located well within the periphery of the disc 7. The edge of the shell is spun down over and against the edge portion of the disc 7, whereby the disc 7 is clamped and elastically held 65 between the edge portions of the shell 2 and the ridge 6, which tightly secures the disc 7 in position.

A means is secured to the disc 7 for connecting the knob to its shank or to a shaft to be manipulated by the knob. The connecting means is so formed that the knob may be readily connected to the movable shaft of an adjustable part of a radio apparatus, for example. The connector 8 may be formed of any suitable metal, such as brass. It is provided with a recess 9 forming a comparatively thin wall 10 at one end of the connector. Also the outer surface of 80 the wall 10 is corrugated or knurled, as at 11, forming engaging teeth or ridges. The connector is forced into a hole formed in the center of the disc 7 and so that the surface of the connector will be tightly pressed 85 against the surface of the hole formed in the disc 7 and so that the teeth or ridges or corrugated surface 11 will engage the disc 7. Thus the disc 7 will be securely keyed to the connector 8. The inner edge 12 of the 90 connector is spun or bent down over the edge of the hole formed in the disc 7 and thus the disc 7 is tightly clamped between the turned edge 12 and the shoulder 13 formed on the connector. The convex shape of the 95 central portion of the shell 2 thus not only forms the distinct ridge for elastically holding the disc 7, but also prevents electrical contact between the shell 2 and the connector 8.

The outer end of the connector 8 may be threaded, whereby the knob may be threaded on the end of a shaft 14 and thus the knob may be securely connected to the movable element or rotor of the part of the 105 radio instrument or other electrical instrument for the purpose of setting or adjusting such movable part.

I claim:

1. In an insulated knob, a shell having 110 an inwardly extending ridge, a disc of insulating material clamped between the edge of

- the shell and the ridge, a rod, means for connecting the insulating disc with the rod.
2. In an insulated knob, a shell having an inwardly extending ridge and a raised central portion, a disc of insulating material clamped between the edge of the shell and the ridge, a rod, means for connecting the insulating disc with the rod and secured to the disc within the area of the raised portion of the shell.
3. In an insulated knob, a shell having an inwardly extending ridge, a disc of insulating material clamped between the edge of the shell and the ridge, a connector having ridges for keying the connector to the disc, a rod connected to the connector.
4. In an insulated knob, a shell having an inwardly extending ridge, a disc of in-

sulating material clamped between the edge of the shell and the ridge, a connector having a corrugated surface for keying the connector to the disc, and having a turned edge and a shoulder for clamping the connector to the disc, a rod connected to the connector.

5. In an insulated knob, a shell having an inwardly extending ridge and a raised central portion, a disc of insulating material clamped between the edge of the shell and the ridge, a connector having a corrugated surface for keying the connector to the disc, and having a turned edge and a shoulder for clamping the connector to the disc, a rod connected to the connector.

In testimony whereof, I have hereunto signed my name to this specification.

GEORGE J. SEISS.
